PROCESS FOR PRODUCING 17-BROMO STEROIDS

Richard U. Schock, Waukegan, and William J. Karpel, Chicago, Ill.; said Schock assignor to Abbott Laboratories, North Chicago, Ill., a corporation of Illinois, and said Karpel assignor to The Glidden Company, Cleveland, Ohio, a corporation of Ohio

No Drawing. Application September 26, 1951,
Serial No. 248,448

7 Claims. (Cl. 260—239.55)

1

Our invention is concerned generally with a novel process for preparing steroid compounds. More particularly, it relates to a process for the preparation of 17-bromo-pregnanolones and pregnenolones from the corresponding pregnanolones and pregnenolones.

The 17-bromo-pregnanolones and pregnenolones prepared by this process are useful in preparing 17-(*a*)-hydroxy compounds which have the configuration present in many of the naturally occurring adrenal hormones. The 17-hydroxy compounds are prepared from the 17-bromo compounds by dehydrobromination, which converts the compound to the Δ^{16} unsaturated compounds, after which this compound is in turn converted to the 16,17-epoxy compound and thence to the 17-hydroxy compound. The 17-hydroxy compound and its 21-acyl derivatives are of current interest in synthesis in the cortisone field, and particularly, Kendall's compound E (pregnene-4-diol-17 (*a*), 21-trione-3,11,20). These compounds are important as adrenal hormones or in therapy requiring this type of compound. These compounds are further useful in the synthesis of similar compounds.

The bromination in the 17-position of pregnanolones and pregnenolones has recently been developed using bromine as the brominating agent. In this respect, reference is made to the publication of Julian and Karpel, Journal of the American Chemical Society, vol. 72, pages 362-6, (1950). The authors disclose the bromination of pregnanolones and pregnenolones using a solution of bromine in acetic acid during which the 17-position is brominated but during which the 21-position and any unsaturated linkages are also brominated. A reduction in the amount of bromine used apparently does not aid in selectively brominating the 17-position. In order to prepare the 17-bromo-derivative, it then becomes necessary to debrominate the 21-position and any previously unsaturated linkage. The authors debrominate by oxidizing with sodium iodide or another reagent followed by reduction of the resulting 21-iodo derivative. This process results in substantial loss in yield and additional expenses in labor and material costs to produce a derivative which is brominated solely in the 17-position. When conducted on a commercial scale, the cost of the 17-bromo derivative is multiplied several times over the process of our invention. The difficulties in debromination are thoroughly discussed by the authors in their J. A. C. S. publication.

According to the present invention, pregnano-

2

lones and pregnenolones are selectively brominated in the 17-position by the use of N-bromosuccinimide. We have discovered to our surprise that this brominating agent produces solely the 17-bromo-pregnanolones and pregnenolones in excellent overall yields. Even when an excess of N-bromosuccinimide is used, the pregnanolones and pregnenolones are brominated selectively in the 17-position and in no other position. We have discovered that with this process it is possible to routinely produce 70 to 75% yields of a 17-bromo-pregnanolone and pregnenolone even in the large scale quantities required in commercial production. These yields are significantly greater than those obtained when using bromine as the brominating agent, followed by dehydrobromination when using either a sodium iodide-sodium bisulfite reaction or when using collidine as the dehydrobromination agent.

We have discovered that our process proceeds satisfactorily without protecting the 3-hydroxy group found in pregnanolones and pregnenolones although we prefer to protect this grouping by acylating with an acyl substituent. We prefer to use the acetyl group as the protecting substituent.

Our process will operate without the benefit of a catalyst but we prefer to use a catalyst. We have used with success both of the usual brominating catalysts; a light source and peroxides. The catalysts are usually defined as "free-radical generating" catalysts. We prefer as a light source the usual photoflood lamps used in photographic work having a high wattage such as the photoflood lamp G. E. RFL 2 lamps currently marketed by the General Electric Company. Similar excellent results have been obtained by using commercial infrared and ultraviolet lamps. We have obtained excellent success using peroxides such as the organic peroxide, benzoyl peroxide.

When brominating unsaturated pregnanolones, it is desirable first to block the unsaturated carbon atoms, for example, with stoichiometric quantities of free bromine, or with chlorine using dichloriodobenzene, (Berg et al., Journal of Biological Chemistry, volume 162, page 683), before brominating with N-bromosuccinimide. After the reaction has taken place, the resulting dihalo compound is treated with alkali-metal iodide and alkali-metal bisulfite as is disclosed in the Julian et al., Journal of the American Chemical Society publication, supra.

By using our process, it is possible to brominate pregnanolones and pregnenolones exclusively in the 17-position even when an excess of N-bromosuccinimide is used. The yields are much higher

than those obtained using other bromination techniques when the 17-bromo compound is desired. Using our process, it is not necessary to resort to the costly dehydrobromination techniques required by the prior art. To the best of our knowledge, this is the only process which brominates directly exclusively in the 17-position of a pregnanolone and pregnenolone. The following equation illustrates the reaction of our process:

The starting materials utilized in practicing the present invention may be represented by the following general formula:

wherein R₁ is selected from the class which consists of hydroxy radicals, acyloxy radicals and hydrogen and R₂ in all three formulae is a radical selected from the class which consists of keto radicals and hydrogen, and such compounds having any unsaturation in any of the rings.

The preferred starting materials are the pregnanolones and pregnenolones, which may contain free or esterified hydroxyl groupings in the molecule, and which may also contain keto groupings. We particularly prefer to use pregnanolones and pregnenolones having an acylated hydroxyl group in the 3-position and a keto group in the 11-position.

When referring to the term pregnanolones and pregnenolones we refer to compounds having the following basic structure:

and compounds having unsaturation in one or more of the rings and to compounds having an acylated hydroxy group in the 3-position.

Examples of our starting materials are: 20-pregnane 3 (α) - hydroxy - 11,20-diketo-pregnane, 3-acetoxy-11,20-diketo-pregnane and 3-acetoxy-11,20-diketo-pregnane, and the like.

In order more clearly to disclose the nature of the present invention, several specific examples illustrating the preparation of typical compounds will hereinafter be described. It should be understood, however, that this is done solely by way of example and is intended neither to delineate the

scope of the invention nor limit the ambit of the appended claims.

EXAMPLE I

17-bromo-11-ketopregnanolone acetate

To a hot solution of 36.5 g. of 11-ketopregnanolone acetate (0.095 mole) in 365 cc. of carbon tetrachloride is added 30.0 g. of N-bromosuccinimide (0.169 mole). The suspension is stirred and heated to boiling, whereupon the heating source is replaced by a photographic photoflood lamp (such as is sold by the General Electric Company under the designation "G. E. RFL 2") and the contents illuminated for 5 minutes. The mixture is chilled, the solids separated by filtration and the filtrate washed with a 10% solution of sodium bisulfite to remove free bromine. After washing twice with water, the wet carbon tetrachloride is distilled in vacuo over a water bath. The crude crystalline cake is slurried with 100 cc. of isopropyl ether and filtered. The yield of 17-bromo-11-ketopregnanolone acetate is 33.0 g., having a melting point of 166-8° C. Upon recrystallization from isopropyl ether the compound melts at 171-2° C. Similar results are obtained with an infrared or ultraviolet source of light or by using a 10 mole percent concentration of benzoyl peroxide.

By refluxing the above crude compound with collidine, a 70-75% yield based on 11-keto pregnanolone acetate of 11-keto- Δ^{16} -pregnenolone acetate may be obtained. This material may then be converted to the epoxy compound and converted to the corresponding 17-hydroxy compound, 11-keto-17(α)-hydroxy pregnanolone.

EXAMPLE II

17-bromo-11-ketopregnanolone acetate

A mixture of 1.9 grams of 11-ketopregnanolone acetate, 20 cc. of carbon tetrachloride, 1.0 grams of N-bromosuccinimide and a few crystals of benzoyl peroxide is heated to boiling under a reflux condenser. After a short time there results a light yellow, cloudy mixture which contains insoluble succinimide. The mixture is cooled to below the boiling temperature. The mass is filtered, and the clarified filtrate is evaporated to a semicrystalline residue. The compound formed is the same compound as prepared by Example I. By refluxing the crude 17-bromo-11-ketopregnanolone acetate, formed above, with collidine, 11-keto- Δ^{16} -pregnenolone acetate (M. P. 160°-164° C., no depression of melting point when admixed with an authentic sample of 11-keto- Δ^{16} -pregnenolone acetate) is produced.

EXAMPLE III

17-bromo-3,9-epoxypregnane-11,20-dione

3,9-epoxypregnane-11,20-dione, M. P. 124-125.5° C., was prepared by chromic acid oxidation of 3,9-epoxy-11-keto-24,24-diphenyl- $\Delta^{20,23}$ -choladiene, M. P. 236-238° C. (according to the process described in Meystre et al., *Helv. Chim. Acta*, 30, 1037 (1947)). The reaction was carried out in an analogous manner to the first example using

0.66 g. of the epoxy steroid (0.002 mole), 20 ml. of carbon tetrachloride and 0.71 g. of N-bromosuccinimide (0.004 mole). There was obtained after recrystallization from methanol 0.45 g. of product, M. P. 213-214° C. (d).

EXAMPLE IV

17-bromo- Δ^5 -pregnene-3(β)-ol-20-one acetate

Since the starting material has unsaturation in the 5,6-position, it is desirable to block the position by the addition of elemental bromine to be removed later by an alkali-metal iodide. The bromine substituted in the 17-position is accomplished by the use of the N-bromosuccinimide.

To a solution of 1.07 g. of Δ^5 -pregnenolone acetate in 20 ml. of chloroform at -70° C. there is slowly added 10 ml. of 0.3 M bromine in carbon tetrachloride solution. After warming to room temperature, the solvents are removed in vacuo. The crystalline residue is dissolved in 30 ml. of carbon tetrachloride. Then about 0.94 g. of N-bromosuccinimide is added and after heating to the boiling point, the flask is illuminated for several minutes with a 250 watt infrared lamp. The mixture is cooled and the solids removed by filtration. The solvent is then distilled from the filtrate at reduced pressure. The residual solid, 5,6,17-tribromo pregnane-3(β)-ol-20-one acetate, M. P. 162-163° (d), is dissolved in 10 ml. of benzene and to this is added a solution of 2.5 g. of sodium iodide in 10 ml. of 12A absolute alcohol. After 24 hours at room temperature, the solution is diluted with water and 50 ml. of ether is added. The layers are separated; the organic layer washed with 10% of sodium bisulfite solution, twice with water and then dried. Evaporation leaves 0.65 g. of product, M. P. 143-145° C. Recrystallization from methanol raises the melting point to 146-147° C.

EXAMPLE V

17-bromo-allopregnanolone acetate

To 1.0 g. of allopregnanolone acetate dissolved in 15 cc. of carbon tetrachloride, 0.6 g. of N-bromosuccinimide and 50 mg. of benzoyl peroxide are added. The mixture is boiled under a reflux condenser for 7 minutes and after being cooled is filtered to remove succinimide. The clarified filtrate is evaporated in vacuo and the gummy residue is taken up in the minimum amount of methanol. The crude product crystallized from this solution melted at 118° to 123° C. (first crop material).

The crude product is recrystallized from methanol resulting in needles of a melting point of 129° to 130° C.

By refluxing the crude material with collidine, 16-dehydro-allopregnanolone acetate is produced which does not depress the melting point of an authentic specimen of this product.

Others may readily adapt the invention for use under various conditions of service, by employing one or more of the novel features disclosed, or equivalents thereof. As at present advised with respect to the apparent scope of our invention, we desire to claim the following subject matter.

We claim:

1. The process of producing a member selected from the class consisting of 17-bromo-pregnolones and 17-bromopregnanolones, which comprises; selectively brominating only the 17 posi-

tion of a member selected from the class consisting of keto pregnanolones and keto pregnenolones with N-bromosuccinimide.

2. The process of producing the compound with the formula:

wherein R₁ is selected from the class which consists of hydroxy radicals, acyloxy radicals and hydrogen and R₂ is oxygen, which comprises selectively brominating only the 17 position of a compound of the formula

with N-bromosuccinimide.

3. Process according to claim 2 wherein one of the rings is unsaturated, which comprises; first saturating the ring with a member selected from the class consisting of chlorine and bromine before specifically brominating the 17-position with N-bromosuccinimide.

4. The process of producing 17-bromo-11-ketopregnanolone acetate, which comprises; selectively brominating only the 17 position of 11-ketopregnanolone acetate with N-bromosuccinimide.

5. The process of producing 17-bromo-3,9-epoxypregnane-11,20-dione, which comprises; selectively brominating only the 17 position of 3,9-epoxypregnane-11,20-dione with N-bromosuccinimide.

6. The process of producing 17-bromo- Δ^5 -pregnene-3(β)-ol-20-one acetate, which comprises; treating Δ^5 -pregnene-3(β)-ol-20-one acetate with bromine in an inert solvent, treating the reaction product with N-bromosuccinimide, evaporating the solvent, adding an alkali-metal iodide, extracting the reaction product with an organic solvent and washing with an alkali-metal bisulfite solution.

7. The process of producing 11-keto- Δ^{18} -pregnenolone acetate which comprises, selectively brominating only the 17 position of 11-ketopregnanolone acetate with N-bromosuccinimide, following by refluxing the 17-bromo compound formed with collidine.
